(57) **CLAIM**

What is claimed is the ornamental design for a pet food container, as shown and described.

DESCRIPTION

FIG. 1 is a front perspective view of the pet food container of Applicant's invention.

FIG. 2 is a rear perspective view of the pet food container of Applicant's invention.

FIG. 3 is a front view of the pet food container of Applicant's invention.

FIG. 4 is a back view of the pet food container of Applicant's invention.

FIG. 5 is a side view of the pet food container of Applicant's invention.

FIG. 6 is a side view of the pet food container of Applicant's invention.

FIG. 7 is a top view of the pet food container of Applicant's invention; and,

FIG. 8 is a bottom view of the pet food container of Applicant's invention.

In the drawings, the dashed lines include environmental structure and form no part of the claimed design.
